UNITED STATES PATENT OFFICE.

ERNEST R. VIBERG, OF MONTREAL, QUEBEC, CANADA.

REFRIGERATOR-CAR CONSTRUCTION.

1,410,277.

Specification of Letters Patent. Patented Mar. 21, 1922.

Application filed June 14, 1921. Serial No. 477,457.

To all whom it may concern:

Be it known that I, ERNEST R. VIBERG, a subject of the King of Great Britain, and resident of the city of Montreal, in the 5 Province of Quebec and Dominion of Canada, have invented certain new and useful Improvements in Refrigerator-Car Construction, of which the following is a full, clear, and exact description.

10 This invention relates to improvements in refrigerator car construction and more particularly to the construction of brine tanks, and the object of the invention is to provide a car available for use as a refrigerator car 15 and as a ventilated car without any adjustment or alteration when converting the car from one use to another.

In ordinary refrigerator car construction, ice bunkers or brine tanks extend up to the 20 hatches and usually occupy the entire end surfaces, so that there is no air passage between the tops of the tanks and the roof. It is frequently necessary to operate refrigerator cars as ventilated cars, that is to say, 25 cars through which a current of fresh air is constantly flowing. In order to do this, it has been customary to provide dampers in the upper part of the tanks or adjacent thereto, so that when these dampers and the 30 icing hatches are open, air may flow through the car. It frequently occurs that the dampers are not open when they should be, either owing to neglect or to some other reason, so that the ventilating of the car cannot 35 be effective. In the same way, dampers are frequently left open when they should be closed, with the result that ice may escape through them into the car or at least damp air escapes from the interior of the tanks 40 into the car.

These disadvantages are overcome according to the present invention by the provision of a fixed slatted portion in the upper part of each brine tank, which will permit air to 45 flow through the car when the hatches are open and which will prevent the escape of ice or damp air into the car when the hatches are closed.

In the drawings which illustrate the invention;—

Fig. 1 is a fragmentary longitudinal section of a car through the icing hatch and illustrating the ventilating plate.

Fig. 2 is a fragmentary cross section of a 55 car showing an elevation of the ventilating plate.

Referring more particularly to the drawings, 11 designates the walls and 12 the roof of a car, which are of usual construction, the roof being provided with a hatchway 13 and inner and outer hatch covers 14 and 15 respectively. The usual brine tanks are designated 16.

According to the present invention, the inner wall of each brine tank is provided at 65 the top with one or more ventilators, designated as a whole by the numeral 17. Each of these ventilators comprises a single plate 18 provided with a plurality of horizontal parallel cuts 19. The material of the plate 70 below each cut is turned outwardly, as shown at 20, so as to provide a comparatively large opening, between each out-turned plate edge and the normal or undisturbed plate edges above the openings. 75 The outturned plate portions are inclined downwardly and toward the tank, as clearly shown in Figure 1, so that the openings 21 are virtually inclined passages leading downwardly into the tank or upwardly out 80 of the tank. The portions 20 may, for convenience, be regarded as transverse slats or bars. In order to protect these slats or bars against distortion by ice thrown into the tank, a plurality of strong, vertically disposed bars 22 are provided inside the plate 18, traversing the openings 21 and the bars or slats 20. The plate 18, while shown as formed of a separate piece attached to the tank, may be the tank wall itself, that is to 90 say, the bars 20 may be pressed from the tank wall and not from a separate plate attached thereto. A splash plate of any suitable form may be disposed immediately below the ventilator 17, as indicated at 23. 95

The ventilator is a fixture and requires no manipulation whatever. The tank may be filled to the top with ice and salt or brine in the usual way. The bars 21 protect the ventilator slats from damage by the ice and, owing to the downward slope of the slats, any water deposited thereon from the melting ice will flow into the tank and not into the car. The splash plate 23 will prevent brine escaping through the ventilator when 105 the car is in motion. Owing to the slope of the passages or openings 21 into the tank, cold damp air in the tank will not flow out through the ventilator, as this would necessitate an upward movement. When it is desired to operate the car as a ventilated car, all that is necessary is to partly open the 110

hatches in the well known manner, indicated in broken lines, Figure 1, so that the hatch cover at the leading end of the car forms an air scoop directing air downwardly 5 through the hatchway and into the upper part of the tank, from which it escapes into the car through the ventilator. It will be noted that the air flows downwardly and must then swirl around and flow upwardly 10 when passing through the ventilator. This reversal of direction causes the greater part of the cinders and dust in the air to drop into the tank, so that they will not be carried into the body of the car. The air flows 15 out through the ventilator and open hatchway at the opposite end of the car in the well known manner. It will be obvious from the foregoing description that, as the slats of the ventilator and the ventilator it- 20 self are fixed, no adjustment will be required

when converting the car from one use to another.

Having thus described my invention, what I claim is:—

1. In combination with an ice tank of a 25 refrigerator car having an opening in the upper part thereof, communicating with the car, a plurality of inclined slats, on the outside of the tank traversing said opening and defining intervening passages leading downwardly into the tank, and vertically arranged protecting bars on the inside of the tank traversing said slats. 30

2. In combination with the structure recited in claim 1, a carrier for the slats and 35 common fastening means securing the carrier and protecting bars to the tank.

In witness whereof, I have hereunto set my hand.

ERNEST R. VIBERG.
